[57] CLAIM

The ornamental design for a faucet handle or the like, as shown and described.

DESCRIPTION

FIG. 1 is a top, perspective view of a faucet handle or the like showing my new design;
FIG. 2 is a top plan view thereof;
FIG. 3 is a side elevational view thereof, the other sides being the same as the side shown; and
FIG. 4 is a bottom plan view thereof.

FIG. 1

FIG. 2

FIG. 3
